UNITED STATES PATENT OFFICE.

ALBERT EMILE ARNAL, OF PARIS, FRANCE.

ARTIFICIAL ARM.

Application filed August 17, 1920. Serial No. 404,084.

To all whom it may concern:

Be it known that ALBERT EMILE ARNAL, a citizen of the French Republic, residing at 14 Avenue des Ternes, Paris, France, has invented certain new and useful Improvements in Artificial Arms, of which the following is a specification.

This invention relates to an artificial arm characterized by the method of assembling 10 and articulation of its various members in such manner as to enable the wearer to carry out all the movements effected by the natural arm and to secure in position and operate with a tool engaged in a suitable device 15 mounted at the end of the arm and constituting the artificial hand mechanism.

To this effect, the device comprises a framework constituting the forearm and having secured thereto the tool holder, the 20 said framework being pivoted to a forked member carrying a leather band whereby the artificial arm is secured to the stump.

The articulation is disposed in such manner as to vary the angular position of the 25 parts thereof as desired or to bring the same into alignment while the device connecting the arm with the forearm provides for the rotation of the latter in such manner as to place the tool in any desired position.

30 The various parts are held in place by locking devices which can be instantly engaged or released by a simple pressure upon the actuating member of the said locking devices.

35 This invention is represented by way of example in the accompanying drawings.

Fig. 1 is a perspective view of the artificial arm.

40 Fig. 2 is a like view with the arm folded back.

Fig. 3 is a separate perspective view of the hook which is adapted to be secured to the forearm.

45 Fig. 4 is a separate vertical section of the device forming a support for the tool holder or the hook.

Fig. 5 is a cross section of the device shown in Fig. 4.

50 Fig. 6 is an enlarged fragmentary bottom plan view of the artificial arm, partly in section, showing certain of the locking devices for the pivoted parts in detail.

Fig. 7 is a vertical section of the same.

55 As observed in Figs. 1 and 2, the apparatus is constituted by a forked member 1

whose branches are riveted to a leather band 2 adapted to receive the stump therein and which is held by means of straps or any other suitable fastening members. To the outer side of the disk shaped base 3 of the forked member 1 is secured by means of a bolt and lock nut 4, a second or intermediate fork shaped member 5 having between the branches thereof a bracket 6. The bolt 4 provides a pivotal connection between the members 1 and 5 and the medial part of the bracket 6 contains a socket 7 having slidable therein a rod 8 connected to a locking member whose end is formed by the pin 9 slidable in the base of the forked member 5. The pin 9 is 70 engageable in any one of the circular series of apertures 10 in the disk 3. The rod 8 is actuated by a coiled spring 11 mounted on the said rod and contained within the socket 7, and in this manner the pin is constantly 75 engaged with one of the apertures 10.

In order to cause the forearm to pivot about the bolt 4 all that is required is to exert a pressure upon the head of the rod 8, thus causing the rod to draw back the pin 80 9 and to disengage the same from the set of apertures 10. This rotation can be carried out through an angle of 180°. To maintain the forearm in the position desired, the rod 8 is released, and the action of the spring 11 85 will cause the pin 9 to again engage the corresponding aperture of the series and will thus secure the forearm in place. The ends of the branches of the intermediate forked member 5 are cross connected by a 90 shaft 12 having pivotally mounted thereon the enlarged ends 13 of the two supports 14, which together with the forked member 5 constitute the forearm.

The two supports 14 are held in the required position by a locking device which is similar to the one employed for the disk 3. The end 13 of each support 14 is provided with a circular series of apertures 15a having engaging therein the pin of each of the locking members 15 secured to the independently movable rods 16 slidable in the branches of the forked member 5 and normally pressed apart by a spring 17 (Fig. 7) whereby to maintain the pins of the locking members 15 100 in the apertures 15a. To bend back the forearm upon the arm or to carry out the contrary movement, all that is required is to press upon the heads of both rods 16 which 105 disengage the pin of the locking member 15, 110

thus releasing the ends 13 and allowing the supports 14 to pivot about the shaft 12 at an angle varying from 0 to 135°.

As hereinbefore mentioned, it suffices to release the heads of the rods 16, whereupon the pins of the locking devices 15, under the action of the spring 17, will again engage the apertures of the ends 13, thus securing the forearm in the desired position. A rod 18 is secured to the supports 14 and coming against a shoulder 18a on the ends of the branches of the forked member 5 serves to limit the angular movement of the supports 14 in the extreme position of the same. At 15 the opposite end of the supports 14 is secured a cap 19 having pivoted thereto a hook 20 (Fig. 3) or a tool holder (Fig. 4) serving the purpose of the hand. Within the said cap is secured a cross piece 21a provided with a depending bracket 21 having pivoted thereto a collar locking member 22 forming part of the rod 23 having the head 24a thereof submitted to the action of a spring 24 disposed within this head. The rod 23 is adapted to move within a longitudinal slot 25 formed in the upper part of the cap 19 and the head of the said rod bears against the edges of the groove 25 wherein it is constantly maintained by the pressure of the spring 24. In front of the cross piece and within the cap 19 is pivoted a second rod 26 adapted to move within a groove 27, the head thereof being spring actuated in the same manner as the head of the rod 23 whereby it is held against the cap 19. A bayonet slot 28 in the end of the cap 19 serves as a guide and a seat for the hook 20. The rear end of the hook is provided with three grooves 29 and ends in a hexagonal portion 30, the grooves and the hexagonal portion are employed to secure the said hook in the cap 19 as will be further set forth.

To insert the hook 20 in place, a movement is given to the rod 23 in the direction 45 of the arrow (Fig. 5) by drawing upon the head thereof, this rod being integral with the locking member 22, whereupon this latter will be moved downwardly. Then the second rod 26 is moved upwardly in the groove 27 in order to permit the free insertion of the stem of the hook 20 which is inserted in wide end of the bayonet slot 28. At this moment, a downward pressure is exerted upon the hook whereby it is caused 55 to cooperate by its two end grooves 29, respectively with the restricted lower portion of the slot 28 and with a recess in the said cross member 21a. To hold the said hook in place it will then suffice to bring back the 60 said locking member by restoring the rod 23 to the initial position, thus causing the polygonal end portion 30 to engage in an opening 23a provided in the said pivoted locking member, the flat sides of this end portion preventing all rotary movement of

the hook. The hook is completely secured in position by bringing down the rod 26 in such manner as to engage the middle groove 29 of the stem of the hook whereby the latter is prevented from moving upwardly in the 70 said slot.

In order to vary the position of the hook 20 it is disengaged at its polygonal end 30 by swinging the locking member 22 on its pivot and turned until the desired position 75 has been obtained, the locking member is then brought back to its original clamping position. The number of faces upon the end 30 may vary according to the number of different positions which it is desired to give to 80 the hook.

It will be understood from the preceding that the artificial arm thus constituted will answer all the purposes of the natural arm for which it is substituted when it is secured to the stump. It forms a light and strong device as a whole, and the pivoting and attaching members are operated in a very convenient manner; the use of the hook or the tool holder which are adapted to the end of 90 the device will allow the wearer to perform manual labor of the most varied kinds without fatigue.

Having thus described the nature of my 95 said invention and the best means I know of carrying the same into practical effect, I claim:

1. In an artificial arm, a member attachable to a stump, a cup-shaped member carried by the first mentioned member, a hook 100 provided with a polygonal extremity adapted for insertion in the cup-shaped member, and means coacting with the polygonal extremity of the hook to maintain the latter in various angular positions with respect to the 105 cup-shaped member.

2. In an artificial arm, a member attachable to a stump, a cup-shaped member carried by the first mentioned member, a hook provided with a polygonal extremity adapted for insertion in the cup-shaped member, 110 means co-acting with the polygonal extremity of the hook to maintain the latter in various angular positions with respect to the cup-shaped member, the shank of said hook being provided with grooves, and means co-acting with said grooves to maintain the hook in position in the cup-shaped member.

3. In an artificial arm, a terminal member, 120 a hook including a shank provided with a plurality of grooves engageable with various portions of the terminal member whereby to limit relative longitudinal movement of the hook and terminal member, and means for 125 maintaining the grooved portions of the hook shank in operative engagement with portions of the terminal member.

4. In an artificial arm, a terminal member, 130 a hook provided with polygonal extremities

insertable in said terminal member, means preventing displacement of the hook relative to the terminal member, and means carried by the terminal member engageable with the 5 polygonal extremities of the hook shank to prevent turning of the latter.

5. In an artificial arm, a terminal member, a hook provided with polygonal extremities insertable in said terminal member, 10 means preventing displacement of the hook relative to the terminal member, and means carried by the terminal member engageable with the polygonal extremities of the hook

shank to prevent turning of the latter, the last mentioned means being mounted for 15 movement relative to the hooked shank whereby to disengage the polygonal extremity thereof, and means to lock the last mentioned means in engaging position.

In testimony, that I claim the foregoing 20 as my invention, I have signed my name in presence of two subscribing witnesses.

ALBERT EMILE ARNAL.
